(57) **CLAIM**

The ornamental design for a protection shield for a catalytic converter, as shown and described.

DESCRIPTION

FIG. 1 is a perspective view of a protection shield for a catalytic converter.

FIG. 2 is a front elevational view of the protection shield for a catalytic converter.

FIG. 3 is a rear elevational view of the protection shield for a catalytic converter.

FIG. 4 is a left side elevational view of the protection shield for a catalytic converter.

FIG. 5 is a right side elevational view of the protection shield for a catalytic converter.

FIG. 6 is a top plan view of the protection shield for a catalytic converter; and,

FIG. 7 is a bottom plan view of the protection shield for a catalytic converter.

1 Claim, 6 Drawing Sheets
